UNITED STATES PATENT OFFICE.

AUGUSTUS H. WARNER, OF BRISTOL, CONNECTICUT.

LANTERN-HOLDER.

SPECIFICATION forming part of Letters Patent No. 247,860, dated October 4, 1881.

Application filed December 13, 1880. (Model.)

To all whom it may concern:

Be it known that I, AUGUSTUS H. WARNER, of Bristol, in the county of Hartford and State of Connecticut, have invented certain new and useful Improvements in Lantern-Holders; and I do hereby declare the following to be a full, clear, and exact description of the invention, such as will enable others skilled in the art to which it pertains to make and use it, reference being had to the accompanying drawings, which form part of this specification.

My invention relates to an improvement in lantern-holders.

Heretofore devices of this character have been of very complicated and hence costly construction, and, moreover, after use of short duration have been open to the objection of rattling disagreeably when the vehicle to which they are attached is in motion. Again, some devices designed for this use have assumed the form of depending cages, while others have had depending arms and clamps extending down for some distance on the body of the lantern. These latter devices have not only been found to be cumbrous in use, but are unsightly in appearance.

In view, then, of the existing state of the art, the objects of my invention are to produce a lantern-holder of extremely simple construction, and hence capable of being produced and supplied to the trade at a slight initial cost, and one which when attached to a vehicle is entirely out of sight and annoyance.

With these objects in view my invention consists in a lantern-holder embodying certain details of construction and combinations of parts, as will hereinafter be described and shown.

In the accompanying drawings, Figure 1 is a view of my lantern-holder with a lantern secured in position therein. Fig. 2 is a detached perspective view of a lantern-holder constructed in accordance with my invention; and Fig. 3 is a view in longitudinal cross-section thereof.

Let A represent a bracket-plate of any desired form of construction, and adapted by means of apertures a to be secured underneath the body of a vehicle. Bracket A is also provided with a blade-shaped depending arm, B, which may be attached thereto, but is preferably cast integral therewith.

Resilient jaws C are riveted at each side of

the arm B, and are adapted, by means of their peculiar configuration, to firmly clasp the central tube of a lantern and support the same. 55 The configuration by means of which this end is attained, consists in a semicircular recess, a', in each of the jaws, and of an outwardly-flaring lip, a². When, now, the two jaws are riveted to the opposite faces of the blade-shaped depending arm B in such position that the convex faces of the semicircular recesses a' are exposed, a cylindrical socket to receive the lantern-tubes will be formed, admission for the tube into the socket being obtained through a 60 wedge-shaped and resilient entrance formed by the conjunction of the two flaring lips of the jaws.

The practical application of my improvement is too simple and apparent to need further 70 explanation than is furnished by the drawings, Fig. 1 of which shows a lantern supported by my form of holder.

The resilient jaws, in addition to the leverage obtained on the center tube of the lantern 75 by their width, are designed to be made of very stiff and highly-tempered metal, and when once in position it will be a practical impossibility for the lantern to work itself free. The under face of the upper cross-tube of the lantern has bearing on the upper edges of the two jaws, and thereby extra support is afforded therefor.

I have shown and described the holder as clasping the center tube of the lantern. However, it is apparent that if any advantage would result two holders of the form described might be placed side by side and adapted to clasp each of the outside tubes of a lantern instead of the central tube. It is also apparent 90 that I should not violate the spirit of my invention by forming a bracket with two depending blade-shaped arms, and providing them with resilient jaws to operate as just above described. Again, instead of having two resilient 95 jaws, one might be made inflexible, though in other respects a counterpart of the flexible jaw. The spring-jaw would in such case operate to force the tube snugly against the rigid jaw, and thus retain the lantern against displacement.

I am aware that spring-jaws have been employed in broom-holders, hat-supports, and oil-can holders, but none of these devices have

been intended or adapted for the purpose of retaining a lantern in place. A lantern-holder must be constructed and arranged not only to support the lantern, but to hold it rigidly and prevent it from swaying or swinging to and fro when the vehicle is passing over rough and uneven roads. To effect these results, I provide a bracket which is adapted to be firmly secured to the under side of the wagon-body, 10 and to a depending arm or lug of the bracket. I rivet the ends of two wide and stiff spring-metal jaws, each of which is provided near its free end with a semicircular recess and with outwardly-flaring ends. The central tube of 15 the lantern being inserted between the wide spring-metal jaws, is retained within the semicircular recesses in said jaws, whereby the lantern serve to not only support the lantern, but, by reason of the extended bearing of the spring-metal jaws on the tube of the lantern, serve to prevent the latter from swinging when suspended beneath a vehicle-body. 20 Having fully described my invention, what

I claim as new, and desire to secure by Letters Patent, is—

A lantern-holder consisting of a bracket-plate adapted to be secured to the under side of a wagon-body, said plate having a depending lug or blade cast integral therewith, in combination with the two wide, flat metal spring-jaws 30 C C, which are riveted at one end to the lower end of the bracket lug or blade, and arranged parallel to the bracket-plate, the free ends of said jaws being formed with an elongated socket for grasping the central tube of the 35 lantern and supporting the same, and also preventing the lantern from swinging while in use, substantially as set forth.

In testimony that I claim the foregoing I have hereunto set my hand this 8th day of 40 December, 1880.

AUGUSTUS H. WARNER.
